UNITED STATES PATENT OFFICE.

SYDNEY C. SWANN, OF RICHMOND, VIRGINIA, ASSIGNOR TO EASTMAN KODAK COMPANY, OF ROCHESTER, NEW YORK, A CORPORATION OF NEW YORK.

CAMERA.

1,394,047.

Specification of Letters Patent.

Patented Oct. 18, 1921.

Application filed March 15, 1916. Serial No. 84,320.

To all whom it may concern:

Be it known that I, SYDNEY C. SWANN, a citizen of the United States, residing at Richmond, county of Henrico, State of Virginia, have invented a new and useful 5 Camera, of which the following is a specification.

It has heretofore generally been the practice in loading and unloading cameras to 10 operate the same in substantially the following manner:

The spool which has been previously used is removed from the center which is ordinarily called the "feed spool" and is placed 15 in a reverse position on the center which is ordinarily called the "winding spool" and the roll is adjusted in the feed center to properly position it. The film paper is then drawn across the exposed face of the camera 20 and the end of the film laboriously inserted into an elongated slot in the winding spool. This film must be accurately centered or it will pull unevenly as is obvious. It is then necessary to turn the finger key several times 25 before putting on the back of the camera. After the camera is closed the winding must be continued until such time as the warning signal on the film indicates that the first film is near position for exposure and con- 30 stant vigilance must be used to prevent the film from passing this point.

Each successive exposure requires the same careful manipulation of the film. After the last exposure is made, the hand winding 35 is continued until previous experience or the operator's judgment indicates that it is probably safe to remove the back of the camera. When this is done the camera must be put upon a suitable table or other support and one hand used to produce a tension on the paper while the other hand winds to the end.

It is furthermore impossible to release the tension until a gummed sticker is put 45 over the end of the roll of the film. Then it is necessary to remove the center and release the roll after which it must be removed or ejected from its pocket by any suitable means, but usually by upsetting or 50 turning upside down or reversing the camera.

In my novel invention, I have devised ap-

pliances for dispensing with the foregoing steps in the manner described which are usually employed in connection with existing forms of cameras now in use, it being unnecessary in adapting my device to camera casings of the conventional type to change to any extent, the exterior contour or casing of the camera, so that my invention is readily applicable to camera casings of the standard types and sizes now in use.

Furthermore in my device I make no change whatever, in the film except to secure a three sided or other polygonal center 65 or reel to the starting end of the roll, said polygonal reel forming the double function both of a reel and center and being made of any suitable material desired, such as paper, pasteboard, fiber, metal or other suitable material and while the same is preferably made hollow, it can be made solid, if desired, and either the hollow or solid construction can be perforated, if desired.

It will be seen from the foregoing that in 75 my device I eliminate various parts of the camera reels and centers heretofore employed and have provided a novel device which is simpler, more efficient and economical and I am further enabled to eliminate 80 the slow and uncertain processes of manipulation now employed to insert a new film or roll.

I furthermore am enabled by my device to expose the film automatically upon pressing 85 a manually operated button and I also am enabled to finally remove said film or roll, after it has been entirely used, from the camera, with greater expedition than heretofore, by means of a novel manual manipulation, which can be readily effected by an unskilled operator.

It further consists of novel tension carrying devices, novel reel centering devices, novel means for simultaneously actuating 95 the centers and novel means to automatically advance the film.

It further consists of a novel film having a gummed tab at its end.

Other novel features of construction and 100 advantage will hereinafter more clearly appear in the detailed description.

For the purpose of illustrating my invention I have shown in the accompanying

drawings a typical embodiment thereof which will give satisfactory and reliable results in practice but it is of course to be understood that the various instrumentalities of which my invention consists can be variously arranged and organized and that my invention is not limited to the precise arrangement and organization of these instrumentalities as herein shown and described.

Fig. 1 represents a sectional view, on line $x-x$ Fig. 2, of a camera embodying my invention.

Fig. 2 represents a section on the line 15 $y-y$ Fig. 1.

Fig. 3 represents, on an enlarged scale, a section on the line $z-z$ Fig. 1.

Fig. 4 represents, on an enlarged scale, a section on the line $w-w$ Fig. 1.

Fig. 5 represents an enlarged view of the construction seen at the right hand end of Fig. 2.

Fig. 6 represents a perspective view, in detached position, of the right-hand center and tension carriage which receives my novel triangular or polygonal reel or center, which I employ in connection with the roll or film.

Fig. 7 represents, on an enlarged scale, 30 a perspective view of one of the operating hubs in detached position.

Fig. 8 represents a side elevation of one of the rock arms employed in detached position seen at the right-hand portion of 35 Figs. 2, 4, 5 and 15.

Fig. 9 represents a section on the line $x'-x'$ Fig. 1.

Fig. 10 represents a perspective view of 40 a roll or film showing the manner of securing the outer or starting terminal thereof, in my novel construction of reel or center.

Fig. 11 represents a perspective view of the opposite or inner end of the roll or film, showing the gummed strip or tab and 45 the upper reel therefor.

Fig. 12 represents a perspective view, in detached position, of the left-hand tension device and centering device seen at the left-hand portion of Figs. 1 and 2 for holding 50 the roll or film in position.

Fig. 13 represents a sectional view of the push button actuating mechanism and its adjuncts seen at the top of Figs. 1, 4 and 9.

Fig. 14 represents a side elevation of an 55 indicator disk employed.

Fig. 15 represents a perspective view of the manually operated device for operating the reel or film centers.

Fig. 16 represents a perspective view of 60 a center pin and the coating center seen in Figs. 1, 3 and 4.

Fig. 17 represents a side elevation of the casing.

Similar numerals of reference indicate 65 corresponding parts in the figures.

Referring to the drawings:—

1 designates my novel construction of camera, the same comprising a casing which may be of any usual construction or conventional character being, if desired, a flat 70 rectangular shape, having round or square ends and provided with a top detachable member 2, which may be fastened in position to the base member 3 by means of any of the spring catches or locking devices 75 now generally employed.

4 and 5 designate the inner side walls of the camera, the same being contained within the outer side walls 6 and 7 respectively, whereby the longitudinally extending chambers 8 and 9, respectively, will be formed between said walls 4 and 6 and 5 and 7 respectively, as will be understood from Figs. 1 and 3.

10 designates a partition at the left of 85 the camera, as will be understood from Fig. 2, and 11 designates a partition at the right thereof, said partition 10 having the roll or roller 12 located in proximity thereto and said partition 11 having a roll or 90 roller 13 located in proximity thereto, said rollers being preferably freely revoluble upon a suitable axis and having the film 14 traveling over them as will be understood from Fig. 2. The manner of mounting or 95 supporting the roll or film 14 will be apparent from Figs. 2, 5, 10 and 11, wherefrom it will be seen that the starting end 15, of the film 14, is secured within the triangular or polygonal shaped reel or center 16 by 100 having its terminal end 17 enter between the juxtaposed walls 18 and 19 of said reel, as will be understood from Fig. 10.

The reel 16 which I preferably employ is shown in the present instance in Figs. 2, 5, 105 10 and 11 as being a hollow triangular or polygonal body, which may be composed of cardboard, paste-board, fiber, metal or other similar material.

The manner of assembling the starting 110 end of the film with respect to its triangular or similar shaped reel 16 will be apparent from the right-hand of Fig. 10, while the inner end of the film as indicated at 20 is provided with a gummed tab or terminal 21 115 which is merely wound around the inner reel 22 but disconnected therefrom, so that when the film 14 has been used on its last exposure the inner end 20 of the film together with the gummed tab 21 can readily be unreeled from the inner reel 22, as will be understood from Fig. 11.

It will be understood that the film 14 comes from the manufacturer wound on the inner reel 22 and having the outer reel 16 125 attached thereto in the manner described with respect to Figs. 2, 10 and 15 and in order to load the camera or to place the film in position, it is only necessary to remove the top 2 of the camera and drop the left- 130

hand portion 23 of the reeled film or roll upon the left-hand tension carriage 24, seen at the left of Figs. 1 and 2 and in Fig. 12, said tension carriage comprising a curved 5 plate having a concave longitudinal seat 25, which receives said roll or reeled film 23. The left-hand tension carriage is provided with eyes or bearings 26, through which the rod 27 passes, said rod having its outer terminals supported in the side walls 4 and 5, as will be understood from the left-hand portion of Fig. 1, wherefrom it will be seen that the left-hand tension carriage 24 is at all times pivotally supported and is capable 10 of a limited amount of movement upon said rod 27, as an axis, said tension carriage being at all times under the action of a tension device, which in its simplest form comprises one of more coiled or other springs 28 having terminals 29 and 30, which bear on the underside of said tension carriage and against the outer surface of the partitions 10, as seen in Figs. 1 and 2, wherefrom it will be seen that the tension of said spring or 15 springs will be to normally raise the lower end of the tension carriage 24, so that as the film 23 is unrolled or unreeled, the tension carriage will contact therewith at all times and will compensate for the reduction in 20 diameter of the roll 23 during the unwinding of the film.

It will be apparent from the foregoing that the roll 23 of the film having been placed in position, as indicated at the left 35 of Fig. 2, will depress somewhat the tension carriage 24 shown at the left of said figure, and the operator can now unroll the film sufficiently until the starting reel can assume the position seen at the right of Figs. 2 and 40 5, it being understood, however, that the inner reel 22 has been previously rotatably mounted in position with respect to its center 31, as will be hereinafter described in greater detail. The manner of mounting 45 and centering the inner reel 22 and the outer or starting reel 16 at each end of the camera being substantially identical, the same will now be described with reference to the right-hand end of Figs. 1, 2, 3, 5 and 15. The 50 film 14 having been unrolled sufficiently, as above explained to permit the starting reel 16 to be dropped into position seen at the right-hand of Figs. 2 and 5, it will be apparent that said reel 16 is received in a longitudinally extending V-shaped seat 32, which is composed of the V-shaped or diverging walls 33 and 34, the latter inclined wall 34 being attached to or depending from the right-hand tension carriage 35 which is composed of the concave or trough-shaped strip or member 36, which is provided with the eyes 37, see Fig. 3, through which the rod 38 passes, as will be understood from the right-hand portions of Figs. 1, 2, 5 and 6. 60 In the construction seen in Figs. 2 and 5, it will be understood that the reel seat 32 is in its extreme highest position, the uppermost position of the right-hand tension carriage 35 being assured by means of the end flanges 39 and the intermediate flanges 40, 70 one of said flanges 40 being shown at the right-hand of Fig. 5 in the position that it assumes with respect to the inner end wall of the lower or base member 3 of the camera. It will be seen that by reason of my 75 novel construction of the tension carriages, coupled with the novel construction of a V or similar shaped seat 32, in the right-hand tension carriage, as soon as the right-hand end of the film, seen in Fig. 2, is unwound to a sufficient extent, it as well as the reel 16, will tend to seek the seat 32 by reason of the slight resilient nature of the film 14, both the inner reel 22 and the outer reel 16 being self centering, by reason of 80 their coaction with the centers 31 and 62, as will be apparent to those skilled in the art.

It will be seen that the upwardly extending terminals or abutments 39 terminate a 90 short distance from the end of the right-hand tension carriage, so that spaces 41 are provided which are occupied by the tension arms 42, seen at the ends of the right-hand tension carriage seen in Figs. 1, 2 and 6, said 95 tension arms being also rotatably mounted upon the rod 38 and provided with coiled springs 43, one terminal 44 of which extends upwardly, as indicated in Fig. 5, while the lower terminal 45 thereof is in contact with 100 the under side of the tension carriage 35. The tension carriage 35 is caused to at all times assume the desired position by means of the coiled springs 46, which have one terminal 47 in contact with the inner curved 105 end wall of the camera, while the other terminals 48 are in contact with the under side of the tension carriage, the function of the terminals 48 being to normally cause an upward tension to be exerted upon the right-hand tension carriage, as will be evident 110 from Figs. 5 and 6.

49 designates a finger piece which projects inwardly and laterally from the upper end of the curved bar 50 which carries in 115 its lower extremity 51 the transversely extending rod 52, whose outer ends are guided in the curved slots 53, see Fig. 5, in the lower portion of the side walls 4 and 5, the outer portions of said rod 52 passing through the holes 54 in the lower extremities of the rock arms 55, whose upper portions are provided with the curved upper slot 56 and the curved lower slot 57.

58 designates an opening in the upper 125 portion of each of the rock arms 55 through which loosely passes the threaded portion 59 of the pin 60 having the finger piece 61 thereon, as will be understood from Figs. 3 and 16. The threaded portion 59 of the 130

polygonal pin 60 carries a triangular shaped center 62 which engages and is inserted in the contiguous end of the starting reel 16.

63 designates cam sleeves which are 5 internally threaded at one end as at 64 in order to engage with the threaded closures 65 which are secured to the end walls of the casing by means of fastening devices 66 and provided with openings 67 through which 10 pins 60 extend. The cam sleeves 63 are provided with the cam slots 68 into which the keys 69 formed by the slots 56 and 57 extend so that when the member 49 is depressed the proper movement will be imparted to the 15 rod 52 and its adjuncts in order to effect the simultaneous actuation of the members 62 to move them into engagement with a reel, as 16, or out of engagement with said reel whereby the latter can be readily removed 20 from the casing.

It will be understood that the centering members 31 at the opposite end of the casing are actuated in a similar manner to the centering members 62. In order to eliminate the 25 necessity of winding up a reel by hand, I provide a winding shaft 70 journaled in the casing in any desired manner and having one end adapted to receive a key whereby the shaft may be rotated. 71 designates a tension 30 spring one end of which is fixed to the shaft and the other end of which is fixed to a stationary part of the device.

72 designates a gear fixed on the shaft 70 and meshing with a pinion 73, mounted on 35 the casing and meshing with a gear 74 mounted on the casing and carrying a ratchet 75. The gear 74 meshes with a gear 76 rotatably mounted on the casing and has connected with it a pinion 77 so as to rotate in unison. This pinion 77 meshes with a rotatably mounted gear 78 which latter meshes 40 with a pinion 79 located within a cam sleeve 63 and loosely mounted on the polygonal shaped portion of a pin 60 so that it will not interfere with the lateral movement of the 45 pin 60 which occurs when the centers for the reel are to be adjusted. The ratchet 75 cooperates with a pawl 80 pivotally carried by the casing and provided with a collar 81 which is fixed to a rod 82 slidably mounted 50 in bearings 83. Interposed between one of the bearings 83 and a washer 84, fixed to the rod 82, is a spring 85. The rod 82 has its free end deflected, as at 86, see Fig. 13, and its outer face is preferably curved in order 55 to coöperate with the hemispherical ball 87 of a plunger 88 which extends through the depressed portion 89 of the casing and is provided with a pressure piece 90 which is 60 normally flush with the outer face of the casing. Against the hemispherical portion 87 bears a pin 91 which passes through a plate 92 and is provided with a flange or shoulder 93 against which is exerted the 65 pressure of a spring 94, it being seen that

the plate 92 is deflected to form a recess or chamber to receive the flange 93 and the spring 94. 95 designates a disk mounted on the shaft on which the ratchet 75 and gear 74 are mounted, said disk having graduations 70 thereon and identifying characters or indicia to indicate the number of exposures on the film; and the outer casing is provided with an aperture 96, see Fig. 17, through which 75 one of the indicia of the disk 95 may be seen so that the user of the camera will know that the film is in proper position to be exposed.

When it is desired to advance the film, the user presses inwardly the presser piece 80 90 thereby causing the rod 82 to release the pawl 80 and permit the ratchet 75 to be advanced one point, which causes the film at the right-hand of the camera to be rotated sufficiently to advance the film to bring the 85 next portion which is to be exposed into proper position with respect to the lens. As soon as the operator releases the presser piece 90 the spring 85 will cause the pawl 80 to engage the next tooth of the ratchet 90 75, as will be evident.

As soon as the entire film has been exposed it is removed in the manner hereinbefore described and a new film is inserted into position. By the employment of my present 95 invention a film can be automatically advanced as desired and the necessity of manually winding the film at each operation is eliminated.

It will now be apparent that I have devised a novel and useful camera which embodies the features of advantage enumerated as desirable in the statement of the invention and the above description, and while I have, in the present instance, shown and described 100 preferred embodiments thereof which will give in practice satisfactory and reliable results, it is to be understood that the same is susceptible of modification in various particulars without departing from the spirit 105 or scope of the invention or sacrificing any of its advantages.

Having thus described my invention, what I claim as new and desire to secure by Letters Patent, is:—

115

1. As a new article of manufacture, a reel 120 polygonally shaped in cross section and having overlapping, juxtaposed, spaced apart lips between which the end of a strip is adapted to be inserted.

2. As a new article of manufacture, a polygonally shaped reel composed of an integral sheet deflected to form a hollow flangeless body having longitudinally extending, overlapping, juxtaposed, spaced 125 lips adapted to receive the end of a strip.

3. In a device of the character stated, a reel of uniform cross section throughout its length and provided with overlapping, juxtaposed, spaced apart lips, whereby a longi- 130

- tudinally extending slot is formed, adapted to receive the end of a strip of material.
4. In a device of the character stated, a flangeless hollow reel of polygonal shape in 5 cross-section and having longitudinally extending, overlapping, juxtaposed, spaced apart lips, between which an end of a strip of material is adapted to be inserted.
5. In a device of the character stated, a 10 reel adapted to receive the end of a strip, a tension carriage resiliently mounted in proximity to said reel, and an extension on said tension carriage adapted to align with and support said reel when the latter is empty.
6. In a device of the character stated, a 15 polygonal shaped reel having longitudinally extending, juxtaposed, spaced apart lips adapted to receive a strip of material, a tension carriage resiliently mounted in proximity to said reel, and an angular shaped extension on said tension carriage adapted to align with and support said reel, when the latter is empty.
7. In a device of the character stated, a 20 reel, centers engaging the ends of said reel, said centers being movable simultaneously into and out of engagement with said ends, a transverse rod extending in a plane parallel to said reel and connections from said rod 25 to said centers for actuating the latter.
8. In a device of the character stated, a reel, centers engaging the ends of said reel, said centers being movable simultaneously into and out of engagement with said ends, a 30 rod extending in a plane parallel to said reel, connections from said rod to said centers, and means for manually actuating said rod, whereby said centers are simultaneously actuated toward and away from each other.
9. In a device of the character stated, a 35 reel, centers engaging the ends of said reel, said centers being movable simultaneously into and out of engagement with said ends, a transverse rod extending in a plane parallel 40 to said reel, and connections from said rod to said centers for actuating the latter, in combination with a finger piece connected to said rod and manually operable in a plane transverse to the axis of said reel.
10. In a device of the character stated, a 45 reel of polygonal shape in cross-section, and having longitudinally extending, juxtaposed, spaced apart lips adapted to receive the end of a strip of material, centers of 50 polygonal shape in cross-section and engaging the ends of said reel, a rod extending in a plane parallel to said reel, connections from said rod to said centers, and means for actuating said rod, connections and centers 55 simultaneously.
11. In a camera, stationary sleeves having cam slots therein, arms having means to engage said sleeves and slots to reciprocate the sleeves, reel centers carried by said arms, 60 and means to rock said arms.
12. In a camera, a casing, sleeves carried thereby and provided with cam slots, arms having means to enter said slots, a rod passing through said arms, means to move said rod in a curved path, and reel centers carried by said arms. 70
13. In a camera, a casing, sleeves carried thereby and having cam slots, arms mounted on and having means to enter said cam slots, pins passing through said arms, reel centers carried by said pins, and means to actuate said arms. 75
14. In a camera, a casing, sleeves carried thereby and having cam slots, arms mounted on and having means to enter said cam slots, pins passing through said arms, polygonal shaped reel centers carried by said pins, and means to actuate said arms. 80
15. In a camera, a reel, a longitudinally extending centering and supporting device 85 for said reel in which said reel is seated when empty, centers engaging the ends of said reel, and means for simultaneously actuating said centers toward and away from the ends of said reel. 90
16. In a camera, a reel, a longitudinally extending centering device in which said reel is seated when empty, centers engaging the ends of said reel, rock arms on each side of said camera, connections from said rock 95 arms to said centers, a rod common to the outer ends of said rock arms, and means for actuating said rod.
17. The combination of a reel adapted to have a strip of material wound thereon, a 100 tension carriage having a portion thereof conforming to the shape of said reel, and tension arms carried by said carriage and bearing against said strip.
18. The combination of a polygonally 105 shaped reel adapted to have a strip of material wound thereon, a tension carriage having a polygonal shaped seat conforming to the contour of said reel and adapted to receive the latter, and tension arms carried 110 by said carriage and adapted to bear against said strip.
19. The combination of a polygonally 115 shaped reel rotatably mounted, of a tension carriage pivotally supported and having a seat therein conforming to the shape of said reel, a spring to move said seat toward said reel, the latter being adapted to have a strip of material wound thereon, arms supported on said carriage, and springs to move said 120 arms toward said reel.
20. In a camera, a photographic film, polygonally shaped reels having overlapping, spaced apart lips between which the ends of said film are received, centers for 125 said reels, and tension carriages pivotally supported and located below said reels.
21. In a film-spool camera including a housing having a posterior opening and a removable cover for same, a pair of opposed 130

pivot members disposed within the casing and adapted to engage opposite ends of a film-spool, and a manually operable member disposed within the camera housing and 5 operable only upon opening the cover for the said posterior opening operatively associated with said pivot-members for simul-

taneously moving the same in opposite directions.
